SHOE

Max W. Borkum, Newton, Mass.

Application June 6, 1957, Serial No. 46,507

Term of patent 14 years

(Cl. D7—7)

Fig. 1 is a top perspective view of a shoe showing my new design.

Fig. 2 is a side elevation thereof.

Fig. 3 is an enlarged fragmentary plan view illustrating in detail the innersole edging.

The essential feature of my design resides in the inner-sole portion shown in full lines in the drawing.

I claim:

The ornamental design for a shoe, as shown and described.
